(57) **CLAIM**

The ornamental design for a combination portable electric toothbrush with travel cover, as shown and described.

DESCRIPTION

FIG. 1 is an exploded view of a combination portable electric toothbrush with travel cover showing my new design;

FIG. 2 is a front perspective view thereof covered by a travel cover;

FIG. 3 is a perspective view thereof without the travel cover;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a bottom rear perspective view thereof;

FIG. 11 is a perspective view of the travel cover that covers the portable electric toothbrush;

FIG. 12 is a front view thereof;

FIG. 13 is a rear view thereof;

FIG. 14 is a left side view thereof;

FIG. 15 is a right side view thereof;

FIG. 16 is a top plan view thereof;

FIG. 17 is a bottom plan view thereof;

FIG. 18 is a bottom perspective view thereof; and,

FIG. 19 is a sectional view taken along line 19-19 of FIG. 17.

The broken lines in the drawings depict portions of the combination portable electric toothbrush with travel cover that form no part of the claimed design. The portable electric toothbrush and the travel cover have been shown separately as well as in combination for clarity of illustration.
